ABSTRACT OF THE DISCLOSURE

Apparatus for the removal of selected bits from the circumference of pattern wheel elements for circular knitting machines, the apparatus comprising holding means for releasably holding one or more pattern wheel elements, mounting means on which a representation of at least part of the repeat pattern area of a fabric to be produced can be mounted, a plurality of selection members each of which can be located, in accordance with information on a representation on the mounting means, to set a separate bit-removing member in or out of a position in which relative movement between it and a pattern wheel element held by the holding means will cause removal of a bit from the circumference of the pattern wheel element, and means for effecting such relative movement. The bit-removing members may be carried on the selection members, and the holding means may be adapted to hold a plurality of pattern wheel elements.

The production of a patterned fabric, by which term we mean a fabric having a freehand or geometric pattern either in stitch configuration or colour, is accomplished on a circular knitting machine by arranging for the cylinder needles to knit, tuck or miss according to a prearranged sequence. As each needle approaches each feeder the needle is selected either to be raised to knit or tuck or not to be raised by the cams associated with that feeder. The characteristics of the cams associated with each feeder dictate the type of stitch formed at that feeder and hereinafter we use the term "knit" as opposed to "miss" to refer to all types of stitch which can be so formed.

One method of selecting the cylinder needles to knit or miss is by the use of pattern wheels. These are devices which are rotated at a prearranged speed in relation to the speed of the cylinder and which have parts and spaces thereon adapted to cooperate with needles or with selector members on the cylinder for selecting needles in consecutive tricks in the cylinder to knit or miss according to the prearranged configuration of the said parts and spaces on the pattern wheels.

One type of pattern wheel operates by having circumferential bits which bear against jacks in the tricks. Each jack is associated with a needle in the same trick and on moving the jack radially in the trick, under the influence of a bit on a pattern wheel, the same jack, a further jack, or the needle in the trick is positioned so as to be ready to be raised or not by a cam associated with the next feeder. Patterning is then achieved by removing or retaining the bits on the pattern wheels.

It has been proposed to make fabrics having increased repeat pattern areas by providing in place of each pattern wheel a number of pattern wheel members each of which can be brought into co-operative relationship with selector members on the cylinder according to a prearranged sequence. This can be accomplished, for example, by moving the pattern wheel members into or out of engagement with selector members on the cylinder by a racking mechanism. Alternatively, all of the pattern wheel mem-

2

bers may be maintained in the same positions but the selector members on the cylinder may themselves be arranged so as to co-operate with different pattern wheel members in sequence. For convenience, hereinafter, we use the term "pattern wheel member" to denote a member which alone, or together with other pattern wheel members, constitutes a "pattern wheel" as referred to above, the member having circumferential bits and/or bit spaces. The arrangement of the bits and/or bit spaces on the pattern wheel member dictates the pattern of a fabric to be knitted whilst the member is controlling the operation of a knitting machine.

In circular knitting machines of fine gauge it has been proposed to use a practice termed "half-gauging." This involves arranging for alternate selector members on the cylinder to cooperate with bits and bit spaces on different pattern wheel elements and enables the dimensions of the bits to be increased. In this case each pattern wheel member comprises two pattern wheel elements each of which has around its circumference half of the number of bits plus bit spaces of the pattern wheel member. Clearly, a further practice, which could be termed "third-gauging," could be adopted in which case each pattern wheel element would have only one third of the number of circumferential bits plus bit spaces of a pattern wheel member, and so on.

The term "pattern wheel element" is used hereinafter to mean an element of a pattern wheel, which is either a pattern wheel member, or which together with one or more other pattern wheel elements constitutes a pattern wheel member, as hereinbefore defined. Such pattern wheel elements have circumferential bits plus bit spaces which co-operate with selector members on the cylinder of a circular knitting machine for determining the pattern of fabrics to be knitted on the machine. A "pattern wheel element" as just defined may constitute a complete pattern wheel or only a part of a pattern wheel.

The full procedure of making a new patterned fabric on a circular knitting machine having pattern wheel elements involves firstly preparing the design for the repeat pattern area of the fabric and then transferring it to squared paper, each square of which represents one stitch in each repeat pattern area on the face of the finished fabric. The next step is to prepare the pattern wheel elements by providing them with the required configuration of circumferential bits and bit spaces. This is a tedious operation involving many hours of exacting work as any mistake made in the configuration of the bits and bit spaces can be difficult to trace and there are often as many as 10-15,000 stitches in the repeat pattern area of a single fabric.

The present invention seeks to simplify the procedure of preparing the pattern wheel elements for the production of a fabric on a circular knitting machine.

According to the invention there is provided an apparatus for the removal of selected bits from the circumference of pattern wheel elements for circular knitting machines, the apparatus comprising holding means for releasably holding one or more pattern wheel elements, mounting means on which a representation of at least part of the repeat pattern area of a fabric to be produced can be mounted, a plurality of selection members each of which can be located, in accordance with information on a representation on the mounting means, to set a separate bit-removing member in or out of a position in which relative movement between it and a pattern wheel element held by the holding means will cause removal of a bit from the circumference of the pattern wheel element, and means for effecting such relative movement.

To shorten the time necessary for preparing all the pattern wheel elements needed for the production of any one patterned fabric, it is preferable to be able to hold

a number of pattern wheel elements on the apparatus at any one time. Where a given number of pattern wheel elements are used in the formation of each course in the repeat pattern area of the fabric to be produced, it is preferred that the same number of pattern wheel elements should be holdable on the apparatus together. If, however, the practice of "half-gauging" is adopted, that is where alternate selector members on the cylinder are contacted by bits from different, complementary pattern wheel elements, it may be more convenient to hold on the apparatus at any one time only the number of pattern wheel elements necessary to form half the stitches in each course of the repeat pattern area, that is either the odd numbered or the even numbered stitches.

It is preferred that the mounting means on the apparatus should be able to accommodate a representation of the whole of the repeat pattern area of the fabric to be produced. A convenient form of mounting means is a drum rotatable about its axis and to which a representation of the repeat pattern area can be attached. Each row on the pattern represents a course in the fabric and the drum is arranged to be rotated, either manually or automatically, so as to bring each row on the pattern to a position at which the marks on that row of the representation can be read by the operator of the apparatus and the position of the bit-removing selection members chosen accordingly.

To shorten further the time taken to prepare the total number of pattern wheel elements for the production of a patterned fabric, it is preferable that a plurality of bits should be removable from each pattern wheel element during each operation of the means for effecting the relative movement between the bit-removing selection members and the pattern wheel elements. This can be accomplished by having a plurality of bit-removing members in operative relationship with each pattern wheel element when relative movement is caused between them. Where the bits and/or bit spaces on each pattern wheel element co-operate with selector members on the cylinder over only a portion of its circumference during each completed revolution of the pattern wheel element, it is preferred that the number of bit-removing selection members in such operative relationship with each pattern wheel element on the apparatus of the present invention should be equal to the number of bits in each such proportion of the pattern wheel element's circumference.

An apparatus embodying the invention is illustrated, by way of example, in the accompanying drawings, in which:

FIG. 1 is a front elevation of the apparatus,

FIG. 2 is an end elevation of the apparatus of FIG. 1, viewed from direction A, and

FIG. 3 is a plan of a pattern wheel element of the type which can be prepared for use by means of the apparatus of FIGS. 1 and 2.

The apparatus in FIGS. 1 and 2 has a frame 1 comprising a base 2 and two integral, vertical end members 3 and 4. A sub-frame 5 comprising two members 6 and 7 and two horizontal rods 8 and 9 is slidably mounted on the frame 1 in plain bearings (not shown) in the end members 3 and 4, through which the rods 8 and 9 pass. The rod 8 has a rack 10 machined in it which is meshed with a pinion 11 which is rotatably mounted on a vertical pivot pin 12. A collar 13 is also fixed to the pin 12 and an arm 14 projects from the collar and carries on its free end a knob 15. Manual movement of the arm 14 in the counter-clockwise direction as viewed from above in FIG. 1 causes rotation of the pinion 11 and thus movement of the sub-frame in the direction of the arrow B and vice-versa. The sub-frame is shown in FIG. 1 at the extreme 70 of its movement towards the right. Movement of the sub-frame 5 in the direction opposite to the arrow B, that is to the position shown, is limited by contact between the end of an adjustable screw-threaded rod 16, passing through the member 7, and the head of a bolt 17 in the 75

end member 4. Movement of the sub-frame 5 in the direction of the arrow B is limited by contact between the head of a bolt 18 in the end member 3 and the end of an adjustable screw-threaded rod 19 passing through the member 6.

The sub-frame member 6 has two mandrel mounting bosses 20 and 21 on shafts (not shown) which are rotatable in plain bearings (also not shown) in the member. On the ends of the shafts are castellated wheels 22 and 23, respectively. Each of the wheels 22 and 23 has eight equally separated castellations 24 and 25, respectively. The member 6 also carries two arms 26 and 27 which are associated, respectively, with the wheels 22 and 23. The arms 26 and 27 are pivoted about pivot pins 28 and 29, respectively, and are spring-loaded by coil springs 30 and 31, respectively, into the position shown in FIGS. 1 and 2 where parts of each of the arms 26 and 27 are disposed in gaps between the castellations 24 and 25 of the wheels 22 and 23, respectively. Rotation of the bosses 20 and 21 is thereby prevented except when the arms 26 and 27 are manually pivoted about the pins 28 and 29 and the said parts of the arms are disengaged from the castellations.

The sub-frame member 7 also carries two mandrel mounting bosses 32 and 33 mounted at the ends of shafts 34 and 35, respectively, which shafts are slidable in plain bearings (not shown) in the member 7. Both of the mandrel mounting bosses 32 and 33 are biased by internal coil springs 36, towards the right in FIG. 1. One of the springs 36 is shown on the shaft 34 of the upper mandrel mounting boss 32 in FIG. 1.

The upper boss 32 is shown projecting to the limit of its movement from the member 7 whilst the lower boss 33 is shown with its shaft 35 as far as possible within the member 7. The shafts 34 and 35 carry rods 37 and 38, respectively, passing through elongated slots 39 and 40, respectively, in the front of the sub-frame member 7. A vertically slidable member 41 is movable across the slots 39 and 40 so as to hold either one of the rods 37 and 38 in a position which the shaft to which it is attached is held largely within the member 7, the shaft 35 being so held in FIG. 1. The slidable member 41 is connected to one end of a "Bowdenflex" cable 42 which passes into a "Bowdenflex" tube 43 the end of which is fixed to a bracket 44 attached to the top of the sub-frame member 7. Manual movement of the slidable member 41, which carries a handle 45 for this purpose, causes movement of the cable 42 in the tube 43, the other ends of both of which are connected to further parts of the apparatus as described below.

Two brackets 46 and 47 are bolted to the backs of the frame's end members 3 and 4, respectively. At the upper end of each bracket there is a plain bearing (not shown) in which a spindle 48 is both rotatable and slidable. A drum 49 is attached to the spindle between the brackets 46 and 47 and two bosses 50 and 51 are clamped to the free ends of the spindle to prevent the spindle from being withdrawn from the bearings but allowing a small degree of axial movement. The free end of the spindle 48 which carries the boss 51 is connected through a lost motion device to the other end of the "Bowdenflex" cable 42 and the other end of the "Bowdenflex" tube 43 is fixed to a bracket 52 attached to the bracket 47. Upward movement of the slidable member 41 thus causes, through the "Bowdenflex" cable connection, movement of the spindle 48 and drum 49 towards the right, as viewed in FIG. 1, whilst downward movement of the member 41 to the position shown causes opposite movement of the drum 49 to the position in which it is shown.

A rod 53 is fixedly held between the end members 3 and 4 of the frame. Forty-eight selection members 54 are pivotally mounted on the rod 53 with spacers 55 between them. The selection members are movable between the two positions designated by the numerals 54a and 54b in FIG. 2. In the position 54a the lower ends 56

of the selection members come into contact with a rod 57 fixed between the end members 3 and 4 and in the position 54b, the top ends 58 of the selection members come into contact with a further fixed rod 59. For convenience, only the six selection members at each end of the set of forty-eight such members are shown in FIG. 1. Each of the selection members 54 has two arcuate cut-outs 60 and 61 in each of which one pin 62 or 63, respectively, is located. The pins 62 and 63 constitute bit-removing members in the present apparatus and these pins are, of course, carried on the selection members.

The selection members 54 are arranged in eight sets of six members in each set, each of the six members in each set having a pin 62 and a pin 63 in different positions from the pins 62 and 63 of other members in the set, as shown in the two sets of selection members shown in full in FIG. 1. In FIGS. 1 and 2 the pins 62 are shown on selection members in position 54a and the pins 63 on selection member shown in position 54b.

A horizontal bar 64 is pivotally mounted on a horizontal pin 65 in the end member 3. With the bar 64 in the position shown in FIGS. 1 and 2 the selection members 54 are locked in one or other of the positions 54a and 54b. However, manual movement of the bar about the pivot 65 allows the selection members to be moved from one position to the other when desired.

A mandrel 66 is mounted on the apparatus between the bosses 20 and 32. The mandrel is freely rotatable in the boss 32, but at its other end the mandrel is keyed to the boss 20 so as to prevent relative rotation between the two. The boss 20 is rotatable only when the arm 26 is moved out of engagement with the castellations on its attached wheel 22 but when the arm 26 is moved out of engagement, the mandrel can be rotated manually by rotation of the wheel 22. The mandrel comprises a central shaft 67 having a keyed end 68 connecting with the boss 20 and a plain end 69 which lies within the boss 32. Mounted on the shaft 67 are nine removable spacers 70a to 70i, numbering from the keyed end 68. Between each pair of adjacent spacers there is a pattern wheel element 71. Each of these is keyed to one of the adjacent spacers 70 and each of the spacers is keyed to the shaft 67 to prevent relative rotation between the shaft and any of the spacers or elements 71 on the assembled mandrel. Each of the spacers 70a to 70i has a differently positioned key (not shown), the keys on the eight spacers being angularly separated from each adjacent spacer by 45° and the positions of the keys being generally on a left-hand helix around the shaft 67.

As shown in FIG. 3, each of the pattern wheel elements 71 is a generally annular disc having forty-eight circumferential bits 72. A slot 73 is formed for keying the pattern wheel element to one of its adjacent spacers 70 on the mandrel 66 and a circular score mark 74 is formed in one side of each pattern wheel element near the roots of the bits for facilitating their removal by use of the apparatus. One bit has been removed from the pattern wheel element shown in FIG. 3 to leave a space 75. The radial length and width of each bit are similar to the dimensions of the pins 62 and 63 on the selector members 54.

The mandrel 66 or an identical mandrel can be fitted between the bosses 21 and 33 in exactly the same way as the mandrel 66 is fitted between the bosses 20 and 32 when necessary, as explained below.

The sequence of operations to use the apparatus involves firstly placing a graphical representation of the repeat pattern area of a fabric to be produced around the drum 49 with the lines representing courses in the fabric lying parallel to the axis of the drum, and the lines representing the wales in the fabric aligned with the selector members 54. A mandrel 66, bearing eight pattern wheel elements 71 in particular relationship, as described below, is then placed either between the bosses 20 and

32 or between the bosses 21 and 33. With the bar 64 moved out of the way of the selection members 54, all of the selection members aligned with squares on the pattern corresponding to particular stitches to be formed are then moved from the position 54a to the position 54b. This movement can be accomplished by the use of a hand tool adapted to grip the top ends of the selection member which can be provided with bevelled parts 76 for this purpose. When all of the selected selection members 54 have been so moved, the bar 64 is moved back into its horizontal position as shown in FIGS. 1 and 2 so as to lock all of the selection members into their selected positions. The arm 14 is then manually moved to cause the sub-frame 5 carrying the mandrel 66 to be moved in the direction of the arrow B in FIG. 1. Each of the pattern wheel elements 71 is thereby moved through the distance occupied by six of the selection members 54. As each bit, if any, on the circumference of the pattern wheel elements projecting from the spacers 70 comes up against any pin 62 or 63 of the selection members, it is broken off at the score mark 74. The sub-frame 5 is then returned to its original position, as shown in FIG. 1. Any bits broken off the pattern wheel elements 71 fall down from the mandrel 66 and are kept away from the rack 10 and pinion 11 by a guard plate 77.

The mandrel 66 is then rotated through 45° to its next position by lifting either the arm 26 or the arm 27, depending on which pair of bosses 20 and 32 or 21 and 33 the mandrel is located between. The arm 26 or 27 is thus removed from the gap between the castellations 24 or 25 on the associated wheel 22 or 23 and then the wheel is turned until the arm engages in the next gap. The bar 64 is then moved out of the way of the selection members so that they can be returned to their positions 54a. If desired, a device (not shown) can be provided to enable all the selection members 54 to be returned together to their positions 54a. This device may comprise a lever connected to a long bar extending the width of the machine in a position so as to engage all the selection members when the lever is pulled.

The drum 49 is then rotated to a new position where a further horizontal line of the repeat pattern area can be scanned by the operator and the appropriate selection members 54 are then moved into the position 54b, before the bar 64 is moved back to the position shown in FIGS. 1 and 2 to lock the selection members into their selected positions. Thereafter bits from the pattern wheel elements 71 are again removed, though this time from further sectors of the pattern wheel elements, by movement of the sub-frame.

This procedure is repeated so that, in all, eight movements of the sub-frame 5 are necessary to remove all of the selected bits from the eight pattern wheel elements held in the apparatus. The mandrel 66 is then replaced by a fresh mandrel carrying eight new, unprepared pattern wheel elements for which the procedure described above is repeated. The elements so prepared on each mandrel are subsequently removed from the mandrels to be mounted onto pattern wheel assemblies for use on a knitting machine.

If desired, an indexing device (not shown) can be provided for the drum 49 to enable it to be located accurately. The device may comprise a plunger spring loaded for engagement in holes located around the periphery of the drum.

The apparatus illustrated in the drawings and described above is particularly adapted for preparing pattern wheel elements of the disc type for use with a circular knitting machine embodying the invention described in the specification of copending U.S. patent application Ser. No. 652,825, filed July 12, 1967, now Pat. No. 3,464,234. One such knitting machine has 1716 needles in its cylinder and a number of pattern wheels disposed around its cylinder, each pattern wheel comprising 8 pattern wheel members each having 96 bits plus bit spaces, a set of 12 bits

plus bit spaces from each pattern wheel member being adapted to co-operate with selector members on the cylinder during each revolution of the pattern wheel and a different set of 12 bits plus bit spaces from each pattern wheel member being so adapted during each of 8 revolutions of the cylinder.

The practice of half-gauging is adopted so that each pattern wheel member comprises two pattern wheel elements, which in the particular embodiment described are of the disc type shown in FIG. 3. Each such pattern wheel element has, therefore, 48 circumferential bits, six of which are adapted to co-operate with selector members on the cylinder during each revolution of each pattern wheel element, 16 of which are mounted on each complete pattern wheel assembly.

In a circular knitting machine having these characteristics, and also being adapted for use with pattern wheels comprising two pattern wheel members, the selector members on the cylinder may be rocking jacks having butts for co-operating with bits on the pattern wheel elements. It is then arranged that the two pattern wheel elements forming each pattern wheel member are positioned on each pattern wheel assembly to have their bits acting on butts in one case above and in the other case below the pivot points for the rocking jacks. Thus to move each rocking jack into one particular position so that a particular operation will be performed by its associated needle at the next feeder, it is possible to use either a bit on an "upper" pattern wheel element or a bit space on a "lower" pattern wheel element, or vice-versa. It follows that on preparing the pattern wheel elements, it is necessary to remove bits from those elements which will co-operate with selector members on the cylinder to form odd-numbered stitches in each repeat pattern area of fabric knitted and to leave only those bits on the elements which co-operate with selector members on the cylinder to form even numbered stitches in each repeat pattern area of fabric knitted, or vice-versa to form a particular stitch on the needles associated with the selector members each time.

It is because of this that the apparatus of the present invention has two mandrel mounting positions, between the pairs of bosses 20, 32 and 21, 33. Mandrels mounted between the upper pair of bosses 20 and 32 are used for preparing pattern wheel elements to be used for forming odd numbered stitches in each repeat pattern area and the lower pair of bosses 21 and 33 are used for preparing pattern wheel elements for forming even numbered stitches in each repeat pattern area. Thus, if a particular selection member is held in the position 54b when the sub-assembly 5 is moved relative to the frame 1, a bit will be removed from a pattern wheel element mounted on a mandrel between the bosses 20 and 32 whereas the selection member has to be in the opposite position 54a to cause removal of a bit from a pattern wheel element on a mandrel between the bosses 21 and 33.

The "Bowdenflex" connection between the slidable member 41 and the spindle 48 ensures that the drum 49 bearing the graphical representation of the repeat pattern area of the fabric is correctly positioned relative to the selection members 54 when pattern wheel elements are being prepared on a mandrel 66 placed either between the bosses 20 and 32 or between the bosses 21 and 33. If the mandrel is held between the bosses 20 and 32, as shown in FIG. 1, the drum 49 is positioned at the extreme of its left hand movement, where the top end of each selection member is aligned, when in the position 54a, with the odd numbered squares of the graphical representation of the repeat pattern area. When a mandrel 66 is placed between the other pair of bosses 21 and 33, for which it is necessary to move the slidable member 41, the drum 49 is simultaneously moved by a shorter distance because of the lost motion device, to a position in which the selection members 54 become aligned with the even numbered squares of the graphical representation. It will

be appreciated, however, that the "Bowdenflex" connection is a refinement in the machine and is not in any way a necessity as the drum 49 could readily be moved axially by hand.

Because of the arrangement, in the circuit knitting machine adapted to use pattern wheel elements of the disc type prepared on the apparatus of the present invention, that each pattern wheel element co-operates with selector members on the cylinder over only one eighth of its circumference, each course of 96 stitches in the repeat pattern area of the fabric is produced by the use of 6 bits plus bit spaces from each of the sixteen pattern wheel elements in the set of pattern wheel elements in each pattern wheel assembly. Eight of the pattern wheel elements are used for forming the even numbered stitches and eight for the odd numbered stitches. The sets of six bits plus bit spaces on each pattern wheel element are offset from each other on the sets of eight pattern wheel elements by 45° so that on revolution of the whole set in the pattern wheel assembly, the six bits plus bit spaces can be brought sequentially into operations with selector members (the butts of the rocking jacks mentioned above) on the cylinder. It is for this reason that when preparing the pattern wheel elements on the apparatus of the present invention it is necessary to mount the elements of each set of eight on the mandrels 66 with their slots 73 offset from each other by 45°. As mentioned above, this is accomplished by providing each of the spacers 70a to 70i with a differently positioned key (not shown) for engaging the slot on its adjacent element 71. When the elements 71 are mounted on each pattern wheel assembly their slots are, of course, aligned.

Use of the apparatus according to the invention greatly facilitates the preparation of the pattern wheel elements for a circular knitting machine, and is particularly advantageous for use with knitting machines capable of knitting fabrics with large repeat pattern areas. Thus, for a knitting machine embodying the invention described in the specification of copending U.S. patent application Ser. No. 652,825, filed July 12, 1967, now Pat. No. 3,464,234, and having 1716 needles and 18 pattern wheel assemblies each having 16 pattern wheel elements with 48 circumferential bits plus bit spaces on each element, the non-spiral, repeat pattern area in two colours is 144 courses by 96 wales. However, to cut the 288 pattern wheel elements together carrying a total of 13,824 bits plus bit spaces only 36 operations are necessary, using eight different elements on a mandrel each time.

What is claimed is:

1. Apparatus for the removal of selected bits from the circumference of pattern wheel elements for circular knitting machines, the apparatus comprising holding means for releasably holding one or more pattern wheel elements, mounting means on which a representation of at least part of the repeat pattern area of a fabric to be produced can be mounted, a plurality of selection members each of which can be located, in accordance with information on a representation on the mounting means, to set a separate bit-removing member in or out of a position in which relative movement between it and a pattern wheel element held by the holding means will cause removal of a bit from the circumference of the pattern wheel element, and means for effecting such relative movement.

2. Apparatus as claimed in claim 1, wherein the bit-removing members are carried on the selection members.

3. Apparatus as claimed in claim 1, wherein the holding means is adapted to hold a plurality of pattern wheel elements.

4. Apparatus as claimed in claim 1, wherein the holding means is adapted to hold the number of pattern wheel elements used in the formation of a course in the repeat pattern area of a fabric to be produced.

5. Apparatus as claimed in claim 1, wherein the holding means is adapted to hold one half of the number of

pattern wheel elements used in the formation of a course in the repeat pattern area of a fabric to be produced.

6. Apparatus as claimed in claim 1, wherein the mounting means is able to accommodate a representation of the whole of the repeat pattern area of a fabric to be produced.

7. Apparatus as claimed in claim 1, wherein the mounting means is constituted by a drum mounted for rotation about its axis and adapted to receive the said representation on its outer surface.

8. Apparatus as claimed in claim 1 and having a separate set of selection members for operating on each pat-

tern wheel element when the said relative movement is effected.
